CLAIM

The ornamental design for a client set-top enclosure, as shown and described.

DESCRIPTION

FIG. 1 is a front perspective view of the client set-top enclosure.

FIG. 2 is a front elevation view of the client set-top enclosure.

FIG. 3 is a rear elevation view of the client set-top enclosure. FIG. 4 is a right side elevation view of the client set-top enclosure. The left side elevation view of the client set-top enclosure is a mirror image of the right side elevation view of the client set-top enclosure.

FIG. 5 is a top view of the client set-top enclosure; and,

FIG. 6 is a bottom view of the client set-top enclosure. The broken lines depict portions of the client set-top enclosure that form no part of the claimed design.
